UNITED STATES PATENT OFFICE.

EDWARD SCHURMAN, OF NEW YORK, N. Y., ASSIGNOR TO SENECA TEXTILE CORPORATION, OF NEW YORK, N. Y., A CORPORATION OF NEW YORK.

DESIGN FOR TEXTILE FABRIC.

Application filed August 29, 1925. Serial No. 14,644. Term of patent 3½ years.

To all whom it may concern:

Be it known that I, EDWARD SCHURMAN, a citizen of the United States, residing in the city of New York, county of Queens, and State of New York, have invented a new, original, and ornamental Design for Textile Fabric, of which the following is a specification, reference being had to the accompanying drawing, forming part thereof.

The single figure of the drawing is a plan view of a piece of textile fabric showing my new design, it being understood that the design is repeated over the surface of the fabric.

I claim:

The ornamental design for textile fabric as shown.

EDWARD SCHURMAN.
